LAWN SWING CANOPY

Artie L. Simpson, San Diego, Calif.

Application September 6, 1957, Serial No. 47,645

Term of patent 14 years

(Cl. D15—11)

The single figure in the drawing is a side perspective view of a lawn swing canopy showing my new design, the dash line showing of a swing being for illustrative purposes only. The end of the canopy, not shown in the drawing, is the same as the end that is illustrated.

I claim:

The ornamental design for a lawn swing canopy, as shown and described.
